UNITED STATES PATENT OFFICE.

GIUSEPPE GAYS, OF LOS ANGELES, CALIFORNIA.

PROPELLER.

958,108.

Specification of Letters Patent. Patented May 17, 1910.

Application filed June 16, 1908. Serial No. 438,818.

To all whom it may concern:

Be it known that I, GIUSEPPE GAYS, a subject of the King of Italy, who have declared my intentions of becoming a citizen of the 5 United States, residing at Los Angeles, in the county of Los Angeles and State of California, have invented new and useful Improvements in Propellers, of which the following is a specification.

10 This invention relates to propellers; and it has for its object to provide an improved device of this character, particularly adapted for aquatic use, which will be relatively simple and inexpensive in construction, positive in operation, and generally superior in 15 point of efficiency and serviceability.

A particular object of the invention is the provision of a propeller for vessel-propulsion, which shall possess a relatively increased degree of operative thrust upon the resisting water, to the end that the water set in motion by the revolution of the propeller shall be utilized as a bearing agency for the propeller through an increased range of propulsive activity, from the point at which the forward portion of the propeller first cuts or engages with a given mass of water to the point at which such mass of water is finally thrown or discharged from the propeller.

20 To this end, I provide propeller members or blades having varied thrust area or operative superficial dimensions; the relative arrangement of said members or blades being such that the member having the least or 25 smallest thrust area is first engaged with a given mass of water, and the member having the most or greatest thrust area is last engaged with said mass of water; one or more members being provided intermediate of 30 those recited with respect to operative position and application to the water and with respect to thrust area. In the employment of a propeller constructed in accordance with the general arrangement, conformation and 35 provision of parts last recited, the water is picked up "dead" by the foremost propeller member and is gradually put in motion as it acts as a bearing in resistance, to the screw action of the propeller, finally leaving the 40 rearmost propeller member at such accelerated speed that its further utilization as a resistance or thrust resistance is substantially null.

45 In the employment of a propeller of the character described, smoothness of operation and lack of vibration accompany the actua-

tion of the propeller, together with a saving of pressure medium and consequently of fuel.

The propeller may be fitted to vessels of 60 standard construction, to which such minor alterations for its reception may be made, as in any particular instance are found necessary.

The invention consists in a novel provision, construction, combination, association and relative arrangement of parts, members and features, all as hereinafter shown and described and finally pointed out in claim.

65 In the drawing:—Figure 1 is a side view 70 of a propeller constructed according to the invention, a portion of a vessel being shown in dotted lines as fitted with said propeller; and Fig. 2 is an end view of the same, looking in the direction of the arrow, Fig. 1. 75

Corresponding parts in both the figures are denoted by the same reference character.

Referring with particularity to the drawing, A, B and C designate respectively, the members of a propeller embodying the invention, in the present instance three of such members or blades being employed. Each of said members or blades represents a portion of the thread of a screw, all of such represented threads having the same 80 pitch; and the stem of said represented screw coincides with the tail shaft D with which the propeller members A, B and C are combined and associated. The thrust areas or operatively superficial dimensions 85 of the members or blades A, B and C vary from and including the member A to and including the member C; so that the member A has the least or smallest thrust area and the member or blade C has the most or 90 greatest thrust area; the said variations in the thrust areas or operatively superficial dimensions corresponding to variations in the depth of cuts of the threads of screws. The member of blade A is located nearest 95 100 adjacent to the forward or inner end portion *a* of the tail shaft D; the member C is located nearest adjacent to the outer or rearward or outer end portion *b* of the tail shaft; and the member or blade B is arranged intermediate of the members A and C. Each of the spiral members or blades extends approximately through 180° of a circle, being fixed at its inner portion to the tail shaft D; and the outer edge portions, 105 *c*, *d* and *e*, respectively, of the propeller member or blades project radially and ob-

110

liquely from the tail shaft D; the edge portion *c*, overlapping the thrust area of the member or blade B; and the edge portion *d* overlapping the thrust area of the member 5 or blade C; to the end that the water passing from the member A is imposed upon the member B and is thence passed to the member C and finally discharged therefrom. The inner portions of the members or blades 10 A, B and C, which connect with the tail shaft D, successively overlap.

The operation, method of use and advantages of the improved propeller constituting the invention will be readily understood 15 from the foregoing description taken in connection with the accompanying drawing and the following statement:—

The member or blade A, leading the other blades, and being first to cut the water, having the smallest or least thrust area, and the thrust areas of the other members or blades being relatively greater, that of the member or blade C being the greatest, and all of said blades having the same pitch; which 25 results that the "dead" water encountered by the blade A will thereby be set in motion, so that when discharged from the blade A to the blade B it will offer less thrust bearing or resistance at any one point of the 30 blade B. But the blade B having more or greater thrust area than the member A it will act upon a greater volume of water than that coming directly into contact with the blade A and thus obtain relatively as 35 much purchase or thrust, in total, as the blade A obtains. The same statement holds substantially true in comparison of the action of the blade C relative to the action of the blade B. When the moving water is 40 finally discharged from the member C it will have become set in motion, by the three propeller blades, to an extent rendering its further utilization as thrust resistance substantially null. It is manifest, therefore, 45 that by the use of the propeller organized as shown and described, substantially all of

the inertia of the water engaged by the propeller is utilized as a purchase for the propeller in its screw action. The overlapping arrangement of the propeller member or 50 blades tends to impart a smooth even motion in the action of the propeller, lessening the jar and vibration usually attended upon propeller action; and the entire operation of the propeller, combining high efficiency 55 and smoothness tends to serve the actuating pressure medium, such as steam, and work a saving of fuel.

I do not desire to be understood as limiting myself to the specific construction, provision, combination, association, and relative arrangement of parts, members and features shown and described; but reserve the right to vary the same, and adapting the improvements to varying conditions of use, 60 without departing from the spirit of the invention or the terms of the following claim.

Having thus described my invention, I claim and desire to secure by Letters Patent:—

An improved propeller having a plurality of spiral members or blades, the inner portion of each of which overlaps the inner portion of each of the others; said spiral members or blades having varying thrust areas or operative superficial dimensions and being of the same pitch, each of said members extending approximately through 180 degrees of a circle; the outer edge portions of said spiral members or blades 75 projecting radially and obliquely from the axis of the propeller; and said outer edge portions overlapping respectively the thrust areas of the adjacent members or blades.

In testimony whereof, I have signed my 80 name to this specification in the presence of two subscribing witnesses.

GIUSEPPE GAYS.
